EDWARD J. FENDERSON, OF LOWELL, ASSIGNOR, BY DIRECT AND MESNE ASSIGNMENTS, TO HERBERT H. HAM, OF BOSTON, AND ALONZO A. COBURN, OF LOWELL, MASSACHUSETTS.

SPINDLE FOR SPINNING-MACHINES.

SPECIFICATION forming part of Letters Patent No. 521,142, dated June 5, 1894.

Application filed January 25, 1892. Serial No. 419,099. (No model.)

To all whom it may concern:

Be it known that I, EDWARD J. FENDERSON, a citizen of the United States, residing at Lowell, in the county of Middlesex and Commonwealth of Massachusetts, have invented a certain new and useful Improvement in Spindles for Spinning-Machines, of which the following is a specification.

My invention relates to spindles for spinning-machines and has for its object to enable such spindles to run steadily at a high rate of speed without being affected by the lateral pull of the driving-band on the whirl. Usually the whirl is rigidly attached to the spindle concentrically therewith and every variation in the tension of the driving-band has a tendency to cause a lateral motion of the whirl and spindle which tendency is resisted by the spindle-supports as bolsters and steps, but as the spindle-supports and the bearing-surface of the spindle become worn the disturbing effect of the driving-band becomes greater. To obviate this effect of the driving-band on the spindle, I make the spindle and whirl in separate parts and support them independently of each other, so connecting them that a rotation of the whirl will produce a rotation of the spindle, while a slight lateral movement of the whirl is not communicated to the spindle.

In the accompanying drawings, Figure 1, is an isometric view of a part of a spindle-rail, the bolster or spindle-support, the spindle and whirl, constructed in accordance with my invention, a bobbin and cap on the spindle and the hook which prevents the spindle from being lifted in doffing; Fig. 2, a front elevation of a part of the spindle-rail and bolster-case, the nut which retains the bolster-case in the rail, the bolster, a part of the spindle and the hook and a central vertical section of the sleeve which forms the lower bearing of the bobbin, the flange of said sleeve, the whirl and the upper part of the bolster-case; Fig. 3, a plan of the spindle and bolster-case and of a part of the spindle-rail; Fig. 4, a central vertical section of the bolster-case, bolster, whirl, sleeve-bearing and an elevation of the body of the spindle.

50 The bolster-case A is supported in the spin-

5 dle-rail B in a well known manner, said bolster-case having an enlarged head or upper end a which rests upon the spindle-rail, the latter being clamped between said head a and a nut a' which turns on a threaded portion a² 55 of the bolster-case against the under side of said spindle-rail. Within a vertical opening in the bolster-case is secured the bolster C, the same having a central vertical opening c to receive the lower part of the spindle D 60 which has a running fit therein in the usual manner.

The body of the spindle D is of the usual form and is made in a separate piece from the whirl E, but is provided with the sleeve 65 d', which usually connects said spindle and whirl, said sleeve serving as the lower bearing of the bobbin F, in the usual manner. If desired, the bolster C may extend up into said sleeve d' in a well known manner. The 70 lower end of said sleeve d' is provided with an outwardly-extending horizontal projection d², represented as an annular flange of about the same diameter as the whirl E, and is provided with one or more radial slots d³ 75 to receive a corresponding number of pins e which project upwardly from the top of the whirl and loosely engage said slots.

The bolster C is provided below its upper end with a shoulder c', represented as a collar or external annular flange, which supports the whirl E, said whirl surrounding the upper part c² of said bolster above said shoulder c' and being separated from the body of the spindle by said bolster. The whirl is provided with a band-groove e', to receive the driving-band in the usual manner. It is evident that a rotation of the whirl in the usual manner will rotate the spindle, the flange d² 80 with its radial slots forming one counterpart 85 and the whirl with its pins e forming the other counterpart of a clutch, but the bolster is so rigid and the pins e are so loose in the slots d³ that any lateral movement of the whirl caused by the tension of the driving-band is 90 not communicated to the spindle. The hook 95 G extends over the flange d² and serves the usual purpose of preventing the spindle from being lifted out of the bolster C in the act of doffing the bobbins and said hook may be 100

turned in the usual manner to allow the spindle and whirl to be removed when necessary.

The top or head a of the bolster-case A is provided, in the usual manner, with a cavity a^3 to receive oil which flows down through an inclined oil-hole a^4 in said bolster-case into an oil-passage a^5 , formed in either or both of the contiguous threaded surfaces a^6 a^7 of the bolster-case and bolster 10 and into an annular space a^7 between said bolster-case and bolster below said threaded surfaces and passes through radial holes a^8 which enter the central opening c of the bolster to lubricate the bearing-surface of the spindle. As the spindle gradually increases in diameter from its lower end to the top of the bolster the rapid rotation of the spindle will carry the oil to the top of the bolster and throw said oil over the top of the bolster, 15 against the sides of the central opening e^2 of the whirl, and said central opening is "rifled" or provided with a shallow left-hand screw-thread, so that the rotation of the whirl, which turns in a right-hand direction or with the sun, carries the oil down to the bottom of the whirl and into an annular chamber a^8 in the top of the bolster-case, said whirl being provided with a downhanging annular flange e^3 which extends into said annular chamber a^8 20 in such a manner that oil dripping from said flange e^3 and thrown outward by centrifugal force will be caught in said chamber a^8 , from which it passes through the inclined oil-hole a^4 which passes through a corner of said chamber, as shown in Fig. 4.

The above described invention is applicable to any spinning, winding or twisting machine in which the spindle is rotated by a whirl and band and in which it is desirable to pre-

vent a lateral motion of the whirl being communicated to the spindle. Said invention also allows of the spindle being removed and replaced without removing the band from the whirl or removing the whirl from its bearing and thereby allows spindles of different lengths to be used with the same whirl. 40

I claim as my invention—

1. The combination of a spindle and a whirl, formed in separate parts, one of which parts has vertical pins, adapted loosely to engage slots with which the other of said parts is provided, with a bolster, having an internal bearing for said spindle and an external bearing for said whirl, as and for the purpose specified. 50

2. The combination of a spindle and a whirl, formed in separate parts, said spindle having a flange provided with slots and said whirl having pins which loosely engage said slots, with a bolster, having separate bearings for said spindle and whirl, as and for the purpose specified. 60

3. The combination of the bolster, provided with an external shoulder, the spindle, supported in said bolster, and a whirl, surrounding said bolster and supported on said shoulder, said spindle having a flange provided with slots and said whirl having pins, loosely to engage said slots, as and for the purpose specified. 65

In witness whereof I have signed this specification, in the presence of two attesting witnesses, this 16th day of January, A. D. 1892.

EDWARD J. FENDERSON.
